CART FOR TRANSPORTING FURNITURE OR THE LIKE

Joe Malits, 18772 Avolinda Drive,
Yorba Linda, Calif. 92686

Filed Jan. 19, 1973, Ser. No. 324,997

Term of patent 14 years

Int. Cl. D12—02

U.S. Cl. D12—29

FIG. 1 is a front perspective view of a cart for transporting furniture or the like showing my new design;

FIG. 2 is a front elevational view thereof along lines 2—2 of FIG. 1;

FIG. 3 is a side elevational view thereof along lines 3—3 of FIG. 2;

FIG. 4 is a side elevational view thereof along lines 4—4 of FIG. 2;

FIG. 5 is a top plan view thereof along lines 5—5 of FIG. 4;

FIG. 6 is a bottom plan view thereof along lines 6—6 of FIG. 4; and,

FIG. 7 is a rear elevational view thereof along the lines 7—7 of FIG. 3.

I claim:

The ornamental design for a cart for transporting furniture or the like, substantially as shown.
